UNITED STATES PATENT OFFICE

ELVIN H. JOHNSON, OF WINNETKA, ILLINOIS

DESIGN FOR A DOOR HOLDER

Application filed July 30, 1931. Serial No. 40,737. Term of patent 14 years.

To all whom it may concern:

Be it known that I, ELVIN H. JOHNSON, a citizen of the United States, residing at Winnetka, in the county of Cook and State of Illinois, have invented a new, original, and ornamental Design for a Door Holder, of which the following is a specification, reference being had to the accompanying drawings, which form a part thereof and in which:

I claim:

The ornamental design for a door holder substantially as shown.

ELVIN H. JOHNSON.
